UNITED STATES PATENT OFFICE

2,589,472

AERIAL DISPLAY APPARATUS

Elliott T. Belmont, Boston, Mass.

Application February 19, 1947, Serial No. 729,455

1 Claim. (Cl. 40—127)

1

This invention relates to aerial display apparatus and it has for its object to provide an apparatus of the class referred to, capable of being used for advertising and other purposes and which will be attractive and interesting to observers on the ground.

To this end I have provided an aerostatic structure provided with a rigid frame equipped with a plurality of buoyant balloons fixed thereto in a manner to delineate a predetermined design and by which the structure is supported in the air. The frame is also preferably equipped with a plurality of electric lamps upon its under side which are arranged in one or more electric circuits by which said lamps are connected with a source of current that is preferably disposed upon the ground, said structure being anchored to the latter by means of one or more guy cables. The lamps are preferably also arranged to delineate said design which, for example, may be an advertisement, and means is preferably provided through which the structure may be controlled from the ground thereby to effect rocking movement thereof so that the design may be seen throughout a greater territory than would be the case when its position is stabilized.

Other features of the invention are hereinafter pointed out.

In the accompanying drawings:

Figure 1 is a bottom plan view of the aerostatic structure.

Figure 2 is a side view of the structure shown in Figure 1.

Figure 3 is an enlarged detail, partly in section on line 3—3 at the left hand end of Figure 1.

Figure 4 is an explanatory view hereinafter described.

Figure 5 is a partial section on line 5—5 of Figures 2 and 6.

Figure 6 is a section on line 6—6 of Figure 5.

Figure 7 is a view like Figure 5 but showing parts thereof in different positions.

Figure 8 is a diagram of the circuits and controls for the valve-operating motor hereinafter described.

Figure 9 is a diagram of the circuits and controls for the pump-operating motor hereinafter described.

The illustrated embodiment of this invention comprises a frame made from light and strong tubing and this frame, as shown, includes two relatively parallel spaced-apart and oppositely disposed side sections 10 and 11, two transverse obliquely disposed sections 12 and 13 with which

2

the opposite ends of a fifth tubular section 14 are connected; the three sections 12, 13 and 14 being disposed so as to form the capital letter A. The opposite ends of the sections 12 and 13 are connected and communicate interiorly with section 10 and section 11, respectively, while the opposite ends of the section 14 are connected with and communicate interiorly with the sections 12 and 13, respectively.

10 The sections 12 and 13 are made interiorly with partitions 15 such as that shown in Fig. 3, said partitions being indicated by dotted lines in Fig. 1.

15 Intermediate its ends section 10 is constructed interiorly with a partition 16 and between this partition and section 13 one end of a relatively perpendicular tubing section 17 is connected with the latter that is in the same plane with sections 12 and 13. The opposite end of section 17 is closed.

20 Section 11 is provided interiorly with a partition 18 that is disposed directly opposite the partition 16 of section 10 and between this partition 18 and section 13 is connected one end of a tubular section 19 which communicates with the interior of section 11 at a point between partition 18 and section 13. Section 19 is disposed in axial alignment with section 17 so that said two sections are capable of being employed to represent the capital letter I. Section 19, like section 17, is closed at its inner end.

25 Another straight tubular section 20 extends perpendicularly from section 10 to section 11 and intermediate its opposite ends this section 20 is provided interiorly with a partition 21. A curved tubular section 22 is connected at its one end with section 20 between partition 21 and section 10 and at its opposite end with the latter. An obliquely disposed tubular section 23 is connected 30 at its one end with the curved section 22 and at its opposite end with section 11. The three sections 20, 22 and 23, together with a portion of section 10, are associated for use in forming the capital letter R. Adjacent to its junction with the curved section 22, the oblique section 23 is made interiorly with a partition that is indicated by dotted lines at 24 in Fig. 1.

35 Two relatively parallel tubular conduit sections 25 and 26 connect sections 10 and 11 each of which is interiorly constructed adjacent its middle with a partition, said partitions being indicated by dotted lines at 27 and 28 in Fig. 1. The outer ends of sections 25 and 26 communicate, respectively, with the interior of section 10 40 at opposite sides of the partition 16 and with

the interior of section 11 at opposite sides of partition 18.

At 29, Figs. 1, 5, 6 and 7, is the body of a valve, said body being made with four ports 30, 31, 32 and 33, Figs. 5 and 7. The port 30 is connected by a branch conduit 34 with the interior of pipe section 25 at a point between partition 27 and conduit 11; the port 31 is connected by a branch conduit 35 with the interior of pipe section 26 at a point between partition 28 and pipe section 11; the port 32 is connected by a branch conduit 36 with the interior of pipe sections 26 between partition 28 and pipe section 10, and the port 33 is connected by a branch conduit 37 with the interior of pipe section 25 between partition 27 and pipe section 10. The branch conduits 34, 35, 36 and 37, together with pipe sections 17 and 19, support the valve body 29 and the latter is provided at its top with a flat face upon which is closely fitted a valve disk or member 38 (Figs. 5, 6 and 7) that is rotatably connected with body 29 by a stem 39 equipped at its lower end with a nut.

The ports 30, 31, 32 and 33 of valve body 29 are spaced-apart angularly 90° and all of them are at the same distance from the axis of the valve member 38 which is made with two arcuate ports 39 and 40 (Fig. 7) disposed diametrically opposite each other, each of which is 90° in length. The arcuate ports 39 and 40 are connected by conduit arms 41 and 42, respectively (Fig. 6), each with one of the two ports provided through the casing of a reversible rotary pump 43 (Figs. 5 and 6) that is mounted upon the top of valve member 38. The shaft 44, Fig. 6, of one of the two rotors of pump 43 extends to the exterior of the casing of the pump and is connected with the armature shaft of a reversible motor 45, Fig. 5, fastened in position upon the top of valve member 38.

Upon its top side the valve member 38 is made adjacent to its periphery with an arcuate rack of gear teeth 46 that is slightly more than 90° in length and this rack is engaged by a pinion 47 fast on the armature shaft of a reversible motor 48 that is fixed in position upon the pipe section 25. Also, the valve member 38 is made upon its periphery with two cams 49 and 50 (Fig. 5) which cooperate, respectively, with make and break stop switches 51 and 52 fixed in position upon pipe sections 17 and 19, respectively. These two stop switches are arranged in circuit with motor 43 as shown in Fig. 8, together with forward and reverse switches 53 and 54.

Normally one of the switches 51 or 52 is held open by one of the cams 49 or 50 while the other switch is closed, as shown in Figs. 5 and 8. Therefore, when the circuit of motor 48, including the closed switch 51 or 52, is also closed at the switch instruments 53—54, the motor 48 acts through its pinion 47 to rotate valve member 38 to the extent of 90° whereupon the closed switch 51 or 52 will be opened by one of the cams of valve 38 thereby stopping motor 48.

Thus, operation of the push-button 53 while stop switch 51 is closed as in Fig. 7, will result in rotation of valve member 38 to the extent of 90° in one direction while operation of push-button switch 54 while switch 52 is closed as in Fig. 5, will cause motor 48 to rotate valve member 38 to the extent of 90° in the opposite direction.

When valve member 38 occupies a position at the limit of its rotary movement in one direction as in Fig. 5, the arcuate port 39 thereof connects the two branch conduits 34 and 37 with one port

of pump 43, while arcuate port 40 connects the two branch conduits 35 and 33 with the opposite port of pump 43. When valve member 38 occupies a position at the limit of its rotary movement in the opposite direction, as in Fig. 7, the arcuate port 39 thereof connects the two branch conduits 36 and 37 with one port of pump 43, while the arcuate port 40 connects the two branch conduits 34 and 35 with the opposite port of pump 43.

While the valve member 38 occupies the position shown in Fig. 5 switch 51 is held open by cam 49 and switch 52 is closed, but when said valve member occupies the position shown in Fig. 7 switch 52 is held open by its cam 50 while switch 51 is closed.

During the movement of valve member 38 from the position shown in Fig. 7 to that shown in Fig. 5, switch 51 remains closed until at the completion of that movement the cam 49 opens the switch 51 and stops motor 48. So also during the movement of valve member 38 from the position shown in Fig. 5 to the position shown in Fig. 7 the circuit of motor 43 remains closed at the switch 52 until the valve member completes such movement whereupon the cam 50 opens the switch 52 and stops motor 48.

The pump motor 45 is caused to operate in one direction by closing a push-button switch 55 and in the reverse direction by closing a push-button switch 56 both of which are in circuit with motor 45 as is also a stop switch 57. It will therefore be clear that when switch 55 is operated while the valve member 38 occupies the position shown in Fig. 5, the pump 43 will be driven in one direction and the contents of pipe section 26 at opposite sides of the partition 28, will be pumped from pipe section 26 and delivered into pipe section 25 at the opposite sides of partition 27 of the latter. It will also be clear that when the pump motor 45 is driven in the opposite direction through operation of the switch button 56, the contents of pipe section 25 at opposite sides of its partition 27 will be transferred, at least in part, to pipe section 26 at opposite sides of its partition 28.

It is also true that when valve member 38 occupies the position shown in Fig. 7 and pump motor 45 is driven in one direction through operation of push-button 55, then the contents of those portions of the interiors of pipe sections 25 and 26 which are at one side of the partitions 27 and 28, will, as indicated by the arrows, be transferred to those portions of the interiors of pipe sections 25 and 26 which are at the opposite sides of said partitions 27 and 28. It will also be clear that the transfer of said contents through the valve mechanism will be in the opposite direction when the motor 45 is driven in the opposite direction.

As shown in Figs. 1, 2 and 3 a multiplicity of elastic rubber balloons 58, 59, 60 and 61 are connected with the top side of the tubular frame of the device and each balloon is fastened to the exterior of a tubular nipple 62 (Fig. 3) through which the interior of said balloon communicates with the interior of the portion of a pipe section to which it is connected. The balloons and tubular frame of the device are filled with helium gas and it will be clear that when the pump 45 is operated, this gas is transferred, in part at least, from one or more groups of balloons to other balloons thus deflating the former and increasing the size of the latter.

The tubular frame, together with the parts carried thereby, is supported in the air at an ele-

vated position by reason of the buoyancy of the balloons while the controlling switches S and S', Figs. 2, 8 and 9, will be disposed upon, or in proximity to, the ground where they are accessible for operation, said switches being connected by circuit cables 63 and 64, respectively, with the apparatus which is anchored to the ground by a steel cable 65, Figs. 2 and 6, whose upper end is fastened to the lower end of the stem 39 (Fig. 6) of the above described valve mechanism.

The valve mechanism shown in Figs. 5, 6 and 7 is disposed at approximately the center of buoyancy of the aerostat and when pump 43 is operated first in one direction and then in the opposite direction while valve member 38 occupies the position shown in Fig. 5, the helium gas will be shifted from one end of the tubular frame toward the opposite end thereof, first in one direction and then in the opposite direction, with the result that the aerostat will be rocked in a direction approximately paralleling a vertical plane at right angles to the pipe sections 25 and 26.

When pump 43 is operated first in one direction and then in the opposite direction while valve member 38 occupies the position shown in Fig. 7, the helium gas will be transferred back and forth from one side to the other of the tubular frame so as to rock the latter in a direction approximately parallel with pipe sections 25 and 26.

It will therefore be clear that when the aerostat is canted, as above described, in either direction its design is displayed to view over a greater territory than would be the case if the aerostat remains in a horizontal position.

To the under side of the tubular frame are secured a multiplicity of electric lamps 66, each of which is provided with a reflector 67. These electric lamps are all arranged in a circuit of which a part is shown at 68 in Fig. 3 and this circuit is also connected with a source of current which may be carried by the aerostat or which may be disposed upon the ground in which latter case the circuit 68 would be extended to the ground for connection with said source. A lamp 66 is provided beneath each balloon and collectively they are grouped to delineate the chosen design which in the present case is the word "Air." The purpose of the lamps is to render the design visible at night and since a balloon is disposed opposite each lamp as shown said balloons also serve to delineate the design during daylight.

The tubular frame of the aerostat is of approximately rectangular shape and the partitions are disposed within the same so as to divide the interior of the frame into four chambers, one at each corner thereof and when the gas is transferred by pump 43 from one pair of chambers to another pair the balloons communicating with the first-mentioned pair will be deflated and those communicating with the other pair will be distended and this will result in tilting the device as described. As further explaining this feature of the invention, I have shown in Fig. 4 a rectangular tubular frame that is interiorly divided by partitions 27', 28', 16', 18', 15' and 21'

into four chambers 69, 70, 71 and 72 connected by branch conduits 37', 36', 35' and 34', respectively, with a control valve 29' like that illustrated in Figs. 5 and 6. When valve 29' occupies the position shown in Fig. 4 and the pump 43 carried thereby is operated in one direction, the contents of the two chambers 69 and 70 will be transferred in part to the chambers 71 and 72 as indicated by the arrows in Fig. 4, while reversal of pump 43 while valve 29' occupies this position will effect the transfer of gas from chambers 71 and 72 to chambers 69 and 70.

Rotative adjustment of valve 29' to the extent of 90° from the position shown in Fig. 4 followed by operation of its pump 43 in one direction, will transfer gas from chambers 70 and 71 to chambers 69 and 72, while reversal of the pump 43 while the valve is in this position will transfer the gas from chambers 69 and 72 to chambers 70 and 71.

In order to stabilize the aerostat and hold it against erratic movements while aloft in a wind, I provide at one end thereof a rudder or stabilizer 73 rigidly fixed to the frame of the device and made with a pair of oppositely disposed vanes that are parallel with the frame and with a vertical vane that is perpendicular to the plane of the frame.

What I claim is:

30 An aerial display apparatus comprising an aerostat and a cable by means of which said aerostat is anchored to the ground, said aerostat comprising a rigid metallic tubular frame having sections thereof disposed to delineate letters; 35 a plurality of balloons fastened to said frame and occupying positions above the latter, said balloons being filled with lighter-than-air gas and communicating with the interior of the frame which is also filled with lighter-than-air gas; a plurality 40 of electric lamps fastened to the under side of said sections of the frame and also serving when illuminated to delineate said letters; a circuit for supplying electric current to said lamps, and a plurality of reflectors carried by said frame 45 each of which is associated with one of said lamps so as to reflect downwardly light that radiates therefrom.

ELLIOTT T. BELMONT.
